UNITED STATES PATENT OFFICE.

CLAYTON A. BROOKS, OF GIRARD, PENNSYLVANIA.

SAFETY DEVICE FOR RAILROADS.

1,221,826.

Specification of Letters Patent. Patented Apr. 10, 1917.

Application filed February 10, 1914. Serial No. 817,802.

To all whom it may concern:

Be it known that I, CLAYTON A. BROOKS, a citizen of the United States, residing at Girard, in the county of Erie and State of Pennsylvania, have invented certain new and useful Improvements in Safety Devices for Railroads; and I do hereby declare the following to be a full, clear, and exact description of the invention; such as will enable others skilled in the art to which it applies to make and use the same, reference being had to the accompanying drawings, and to the letters of reference marked thereon, forming part of this specification.

My invention relates to safety apparatus and devices for railroads and has for its object the construction of mechanism adapted to be automatically operated to cut off the power and set the brakes of trains when the speed thereof exceeds the predetermined maximum, or which may be set to stop a train at a desired station-stop.

In carrying out the objects of my invention I provide a governor mechanism, and trip mechanism which so coöperate as to open an air-valve, when the predetermined rate of speed is reached by the train, so as to admit air to pneumatic valve-mechanism designed to turn air into pneumatic mechanism to cause a disconnecting of the throttle operating lever, and simultaneously close the throttle-valve and set the brakes of the train.

The features of my invention are hereinafter fully set forth and pointed out, and are illustrated in the accompanying drawings, as follows, viz:—

Figure 1, is a view partially in section, showing a diagrammatic arrangement of a portion of mechanism and apparatus for carrying out the objects of my invention.

Fig. 2, is a diagrammatic view of a portion of apparatus suitable for carrying out the objects of my invention, showing an arrangement of trip mechanism, and governor driving mechanism.

Fig. 3, is a transverse section of the throttle lever unlatching mechanism on the line *x*, in Fig. 1, looking in the direction of the arrow.

Fig. 4, is a longitudinal section of a fragment of the same.

Fig. 5, is a view in elevation of a portion of the governor-operated mechanism of my apparatus.

Fig. 6, is a transverse section of a portion

of my apparatus on the line *y*—*y*, in Fig. 1, looking in the direction of the arrow.

Fig. 7, is a transverse section of the throttle lever unlatching mechanism, showing an alternative construction of the latch mechanism.

Fig. 8, is a side elevation of a fragment of the same.

Fig. 9, is a rear end view in elevation of a car truck and portion of rail way track showing an arrangement of trip mechanism.

Fig. 10, is a plan view of a fragment of rail-way track showing an arrangement of trip mechanism, according to my invention.

In these drawings A, indicates a throttle-valve-stem, and A', a portion of a locomotive boiler. The valve-stem A, is provided with a notch *a*, (see Fig. 4, and shown in broken lines in Fig. 1). Slidably mounted upon the valve-stem A, there is a latch-block A², which is connected with the throttle-operating lever, A³, by means of a link *a'*. The latch-block A², is provided with a transverse slot *a*², in which is placed a vertically movable latch-bar *a*³, which is secured to the arms *a*⁴, of a weight *a*⁵, by means of which the latch-bar *a*³, is normally retained in the transverse notch *a*², in the valve-stem A, so that the same may be operated by the throttle lever A³, in the usual manner.

Upon the boiler A', I secure a yoke B, which supports a cylinder B', concentric with the valve-stem A, and into which said valve-stem will extend when the throttle-valve is opened. In this cylinder there is a piston B², which will operate against the end of the valve-stem A, under conditions hereinafter pointed out. To one of the arms of the yoke B, there is another cylinder B³, in which there is a piston B⁴, and which is secured on a piston-rod B⁵, which extends through the yoke B, and has on its end a plate B⁶, of a length co-extensive with the maximum travel of the valve-stem A, in the opening and closing of the throttle-valve of the locomotive.

From the cylinder B³, to the cylinder B', an air duct 1, extends, the forward movement of the piston B⁴, opening the intake end of said air duct 1. The cylinder B³, is provided with a vent opening *b*, with which the duct 1, communicates when the piston B⁴, is in its lower-most position.

I also provide a transverse opening *b'*, through the neck of the cylinder B³, and a transverse opening *b*², through the piston-rod B⁵, which, when the piston B⁴, moves to

its uppermost position coincides with the opening b' , to permit of the passage of air therethrough. From one end of the opening b' , an air duct 2, communicates with the 5 air pipe 3, of the train, beyond the engineer's valve 4. The other end of the opening b' , is provided with an air-duct 5, which leads to a cylinder C, in which there is a piston C', having a transverse opening therethrough, 10 which coincides with the opening c , communicating with said air-duct 5, and a vent opening c' , in the wall of said cylinder, when said piston C', is in its normal position as shown in Fig. 1; the piston C', is 15 provided with a reduced end C², which operates in a reduced portion of the cylinder C. From the large end of the cylinder an air duct 6, through the air-duct 2, communicates with the air-pipe of the train beyond 20 the engineer's valve, and from the smaller end of the cylinder C, an air duct 7, communicates with the source of air supply through the main air duct 8—9.

Communicating with the air duct 7, is a 25 cylinder D, in which there is a piston D'. The cylinder D, has an enlarged longitudinal extension D², in which there is a piston D³, which is connected with the piston D, by a rod d. The piston D³, has a transverse 30 opening d', therethrough which communicates with openings d² and d³, in the wall of said cylinder. This piston D³, also has a recess d⁴, of sufficient length to span the opening d', and the opening d⁵, in the wall 35 of the cylinder D², simultaneously when said piston D³, is in the position thereof shown by broken lines in Fig. 1. From the opening d⁵, in the cylinder D², a duct 10, communicates with the cylinder B³, and the 40 main air ducts 8—9, from the source of air supply (not shown) to the engineer's valve 4, through the openings d² and d³, and the transverse opening d', in the piston. From the large end of the cylinder D², an air-duct 45 11, leads to a cylinder E, and communicates therewith through an opening e; another air-duct 12, also communicates with said cylinder E, through an opening e', in the wall thereof and with the main air-pipe 8, from the source of air supply. Within the 50 cylinder E, there is a piston E', having a transverse opening e², therethrough. This piston E', also has a portion thereof cut away so as to form an off-set e³, at one end thereof, which, when the piston E', is in its 55 normal position as shown in Fig. 1, will have the opening e, in the wall of the cylinder uncovered, and when the piston E', is in the position thereof shown in broken 60 lines, the air duct 11 and 12, will communicate through the transverse opening e². The piston E', is provided with an operating rod E². The cylinders C and D², are each provided with vent openings c² and d⁶, and 65 the piston B⁴, is provided with a spring b³,

to force a return of said piston to its normal position. The operation of the mechanism hereinbefore described is as follows, viz.— The piston valve E', is moved to the position thereof shown by broken lines in Fig. 1, 70 which admits air from the main air pipe 8, through the air ducts 11 and 12, into the cylinder D², which, owing to the large area of the piston D³, as compared with the piston D', the piston D³, forces the piston D', 75 backward against the air in the air-duct 7, and communication between the air ducts 8 and 9, is closed, and communication between air ducts 8 and 10, is opened so that air from the main air duct 8, will pass through 80 duct 10, into cylinder B³, and force piston B⁴, therein upward and thereby through the plate B⁶, and weight a⁵, lift the latch-bar a³, out of the notch a, in the valve-stem A, which leaves the latch-block A², free to 85 slide on the valve-stem A, without moving the same. Simultaneously with lifting the latch-bar a³, the piston B⁴, uncovers the opening from the cylinder B³, into air duct 1, and air flows therethrough into cylinder 90 B¹, and forces piston B², forward against the end of the valve-stem A, and moves the same to close the throttle valve. The upward movement of the piston B⁴, and piston-rod B⁶, also simultaneously brings the 95 transverse opening b², therethrough into coincidence with the opening b', which permits air from the train pipe 3, to exhaust out through air duct 5, until the pressure in the train pipe is reduced sufficiently to 100 allow air in the duct 7, acting on the small piston to overcome the pressure on the large piston C', and move said piston C', backward so as to close the passage through said piston and stop the escape of air from the 105 opening c', in cylinder C. The apparatus will then continue in this condition until the piston E', in the cylinder E, is returned to the position thereof shown by full lines in Fig. 1, which cuts off the supply of air to the cylinder D², and opens the duct 11, to exhaust through the opened end of the cylinder E, when the air in duct 7, acting on the small piston D', forces piston D³, back into the position thereof shown in full lines 110 in Fig. 1, again letting air from the main duct 8, in the duct 9, and cutting the same off from duct 10, and cylinders B³, and B¹, allowing the spring b³, to force piston B⁴, back to its normal position as shown by full 115 lines in Fig. 1, simultaneously allowing air in cylinders B¹ B³, and D², to exhaust through the vent openings b, and d⁶. When the pressure in the train pipe 3, and air duct 2, is again raised to normal, 120 the piston C', in the cylinder C, will thereby be forced backward into the position thereof shown by full lines in Fig. 1, again opening the duct 5, to exhaust through the opening c', the larger diameter of the piston C', 125 130

forcing the smaller piston C², backward against the air in duct 7. The engineer can now move the latch-block A², along on the valve-stem A, until the latch-bar a³, again drops into the notch a, when the valve-stem can be again operated as usual. The piston E², not being secured to the valve-stem A, after being moved backward into the position thereof shown by full lines in Fig. 1, 10 does not move therefrom when the valve-stem A, is manually operated.

The cylinder E, is mounted upon a frame or inclosed case E², through which its operating stem or handle E², extends, and which 15 is provided on its extremity with a loop or knob E⁴. For automatically forcing the piston E', forward, a spring e⁴, is provided. The stem E², is provided with a notch e⁵, which is entered by a dog F, which dog is 20 retained in engagement with said notch e⁵, by means of a spring pressed rod F', to which a trip wire H², is secured. Pivoted in the frame E², there is a spring actuated latch-dog G, which, under certain conditions 25 hereinafter described, when released by the spring pressed hook G', is adapted to engage a notch e⁶, in the stem E², of the valve E', when the same has been released by the dog F, and prevent a manual return 30 of the same to its normal position. The hook G', is mounted upon a bell-crank lever G². Secured upon the spring pressed bar F', there is a shoulder f, and extending from one arm of the lever G², to the 35 shoulder f, there is a post or link G³, having an offset g, at its lower end. For operating the bell-crank lever G², I mount in the case E², an oscillating frame H, (see Figs. 5 and 6) in which there is mounted a rock-shaft 40 H', upon which are adjustably secured 45 spring-pressed fingers h, h', and h². I also secure upon said rock-shaft H', arms h³. For causing the frame H, to oscillate, I provide a governor mechanism J, from which 50 a vertically movable stem J', extends upwardly. Pivoted in the case E², there is a bell-crank lever J², one arm of which engages the stem J' the other arm of said lever being connected with the frame H, by 55 means of a link J³. Pivoted to the upper end of the stem J', is a post K, which, when the governor mechanism is at rest should 60 extend upwardly to the latch-dog G, so as to prevent any movement of the same, 65 should the hook G', release said latch-dog while the governor is at rest. Pivoted in the frame E², there is another spring pressed bell-crank lever L, one arm of which extends over the arms h³, and pivoted upon 70 this bell-crank lever L, there is a spring pressed guide arm L', adapted to support and guide the upper end of the post K. I secure to one arm of the bell-crank lever L, a bar L², having teeth l, adapted to be engaged by the spring operated hooked-lever

M, when the same has been released by forward movement of the valve-stem E², and the stud m, thereon, so as not to change the position of the bell-crank lever L, and the guide arm L', and post K, until the 70 valve-stem E², has been moved back to its normal position. I have provided electro-magnetic mechanism for operating one of the fingers h, consisting preferably of a solenoid N, the core of which is connected with one of said fingers. On the hub of the frame H, I provide a circuit interrupter n, with which brushes n', contact, which brushes are in circuit with said electro-magnetic device. I also place in said circuit a circuit 75 breaker n², which, when the operation of the electro-magnetic device has caused the dog F, to release the valve-stem E², breaks said circuit so that said dog will be released to again engage the notch e⁵, in said valve-stem when it returns to its normal position. From the fingers h, and h', trip wires H², and H³, extend to trip mechanism 80 hereinafter described.

In Figs. 7 and 8, I illustrate another form 85 of throttle lever latch mechanism, in which the latch O, is pivoted upon the latch block A², above the valve-stem, and is operated by means of a spring-pressed bar O', 90 slidably mounted in ears on the side of said latch-block A², and engages a slotted lever O², on said latch O, the lower end of the slide-bar O', contacting with the piston operated plate B', by which it may be operated to move 95 said latch O, out of the notch a, in the 100 valve-stem A.

The governor mechanism J, is operated by means of a driving-belt P, which is passed around a pulley P', operatively connected with said governor mechanism and a 105 pulley P², on one of the locomotive wheel axles P³, so that variations in speed of rotation of said axle will be communicated to said governor mechanism.

Pivoted upon suitable supports on the locomotive truck mechanism Q are bell-crank levers R, R', and R², to one arm of each of 110 which levers, the trip wires F², H² and H³, are secured, and between the track-rails S, are secured trips T, T', and T², (see Figs. 115 9 and 10), the trips T, and T', being secured in such position that they will engage and actuate the levers R', and R², and the trip T², being provided with shifting mechanism r, r', and r², by means whereof it may 120 be moved into position to engage the lever R, and operate the same when desired, or removed from such position, when desired; thus, if it is desired to stop the train at a certain station the tower-man can throw the trip T², into position to engage the lever R, which, when operated thereby pulls the trip wire F², and spring-pressed bar F', and 125 disengages the dog F, from the notch e⁵, in the valve-stem E², and the valve E', then moves 130

forward into the position thereof shown by broken lines in Fig. 1, when the power will be shut off, and the train brakes set as hereinbefore described, but the engineer can immediately draw the valve-stem E^2 , back to its normal position where it will be again held by the dog F , and he can again operate the throttle valve-stem A , by means of his lever A^3 , the train brakes being released by the return of the valve-stem E^2 , to its normal position.

Trips T , and T' , operate the levers R' and R^2 , to pull the trip-wires H^2 , or H^3 , to cause the fingers h , and h' , to tip downward, when one or both of said fingers will engage offset g , on the bar G^3 , and force it downward, thus causing the dog F , to release the valve-stem E^2 , so that the spring e^4 , may force the valve E' , forward, and will simultaneously cause the hook G' , to release the latch G , which will lock the valve-stem E^2 , in its forward position as shown by broken lines in Fig. 1, and the arm h^3 , will be raised so as to lift the tooth-bar L^2 , upward so that the hooked lever M , will engage one of the teeth and retain the bell-crank lever L , in the lifted position so as to support the post K , in proper position under the latch G , to operate said latch G , to disengage said latch from the notch e^6 , in the valve-stem E^2 , when the slowing down of the governor mechanism causes said post K , to move upward against said latch G . The latch G , is provided with steps g' , g^2 , and G^3 , to correspond with the fingers h , h' , and h^2 , both of which represent different rates of speed, which, when exceeded will, by the coöperation of the governor mechanism J , and trips T , and T' , and the electro-magnetic mechanism N , cause the mechanism hereinbefore described, to reduce the rate of speed to the required point, before the valve-stem E^2 , will be released by the action of the governor J , through the post K , and latch G , so that the engineer can draw the valve-stem E^2 , back to its normal position. Accordingly, when the frame H , is oscillated by the governor mechanism J , when the train exceeds a rate of speed of, say, twenty-five (25) miles an hour, the finger h , will be over the off-set g , on the bar G^3 , and the upper end of the post K , will be withdrawn sufficiently from the step g' , on the latch G , to permit the latch, when released, to engage the notch e^6 , in the valve-stem E^2 ; the lever R^2 , strikes the trip T , and thereby pulls down the finger h which engages the off-set g , on the bar G^3 , operates the dog F , to release the valve-stem E^2 , and operate the hook G' , to release the latch G , to lock said valve-stem in said forward position, the hooked lever M , meanwhile having engaged the toothed-bar L^2 , thereby holding the upper end of the post K , in position under the relative step on the latch G , so that when the slowing down of the train and

governor J , raises the post K , upward and thereby forces the latch G , out of engagement with the notch e^6 , in the valve-stem E^2 , and into engagement with the hooked lever G' , when the valve-stem E^2 , is again free for the manual operation of the engineer.

The trip T' , is for the purpose of performing the same operation as above described, when the train exceeds a speed of, say, forty (40) miles an hour, the governor mechanism J , oscillating the fingers h , h' , and h^2 , far enough for the finger h' , to be over the offset g , when the operation of the lever R' , by the trip T' , will, as above described, release the valve-stem E^2 , the governor mechanism J , drawing the post K , far enough downward for its end to engage the step g^2 , on the latch G , when the lever L , is operated by the arm h^3 , to push said post under said step g^2 ; and when a rate of speed of, say, fifty (50) miles an hour is reached, the governor mechanism will turn the frame H , far enough that the finger h^2 , will be over the offset g , and the circuit interrupter, n , will close the circuit through the electro-magnetic device N , which will then, through lever U , pull down the finger h^2 , and the mechanism will operate to slow down and stop the train as hereinbefore described.

The rates of speed herein mentioned, it will be understood, are only mentioned as examples, as the governor mechanism J , and fingers h , h' , and h^2 , can be regulated for any speed required, the operation of the mechanism remaining the same. It will also be understood that the number of rates of speed may be increased or diminished as desired, by adding fingers and trips.

When a low rate of speed is required, as at a down grade, or at a curve, or bridge, a trip for the required speed can be placed in the track, and when the train passes the trip its speed will be reduced automatically to the required rate, before the engineer can move the valve-stem E^2 , back to its normal position, to reverse the action of the mechanism hereinbefore described, so that he can again open the throttle of his engine.

Having thus fully described the construction and operation of my invention, what I claim as new and desire to secure by Letters-Patent is:-

1. In an apparatus of the character described, a throttle-valve-stem, a latch-block slidably mounted thereon, an operating lever operatively connected therewith, cylinder and piston mechanism adapted to move said valve-stem to close said throttle-valve; cylinder and piston mechanism adapted to release said latch-block from engagement with said valve-stem, an air-duct from the last mentioned cylinder to the first mentioned cylinder having the entrance thereinto from the last mentioned cylinder so located as to be uncovered by the piston therein, and

valve-mechanism adapted to admit air into the last mentioned cylinder, substantially as described.

2. In an apparatus of the character described, a throttle valve-stem having a transverse notch therein, a latch-block slidably mounted on said valve-stem with which the throttle operating lever is connected, a latch on said block so as to prevent said block from sliding on said valve-stem, a cylinder, a piston therein adapted to operate against the end of said valve-stem, a cylinder secured transversely to said valve-stem, an air duct leading from the last mentioned cylinder to the valve-stem operating cylinder, a piston and piston-rod in said transverse cylinder, a plate parallel with said throttle-valve-stem secured on the end of said piston-rod and adapted to raise said latch out of said notch when its connected piston is operated, said last mentioned piston being adapted to act as a valve to open communication from its cylinder into said air duct, and valve mechanism, to admit air into said last mentioned cylinder, substantially as set forth.

3. In an apparatus of the character described, a valve-stem having a notch therein, a latch-block slidably mounted thereon and connected with the throttle operating lever, a yoke having the arms thereof parallel with said valve-stem, a cylinder supported by said yoke, concentric with said valve-stem, a piston in said cylinder, a latch pivoted in said latch-block above said valve-stem, an arm on said latch, a spring pressed rod engaging said arm and slidably mounted on the side of said latch-block, a cylinder secured to one arm of said yoke, and having an opening in the wall thereof, a piston in said cylinder adapted to uncover said opening on its upward movement, a piston rod secured thereto and extending upward through said yoke arm, a plate on the upper end of said piston-rod adapted to engage said spring-pressed rod and raise the same to operate said latch, an air duct leading from said opening in the wall of said cylinder to the cylinder concentric with said valve-stem, substantially as and for the purpose described.

4. In an apparatus of the character described, a throttle-valve-stem, a slidable block thereon, latch mechanism for securing said block non-slidably on said valve-stem, a throttle operating lever connected with said latch mechanism, piston mechanism to operate said latch mechanism an air duct communicating with the main train pipe, valve mechanism controlling the air passage in said duct operable by said piston mechanism, piston mechanism adapted to operate said throttle-valve-stem, an air duct forming communications between said piston mechanism and valve mechanism to

admit air to said piston, substantially as described.

5. In an apparatus of the character described, piston mechanisms for disconnecting the engineer's throttle operating lever, closing the throttle-valve and reducing the pressure in the train pipe, pneumatically actuated valve mechanism for admitting air to said piston mechanisms, and valve mechanism for controlling admission and exhaust of air to and from said pneumatically actuated valve mechanism, substantially as and for the purpose set forth.

6. In an apparatus of the character set forth, piston mechanisms for disconnecting the engineer's throttle operating lever, closing the throttle valve and reducing the pressure in the train pipe, valve mechanism for controlling admission and exhaust of air to and from said piston mechanisms, a spring to actuate said valve in one direction, a valve-stem for operating said valve in the opposite direction, a spring pressed dog to maintain said valve open to exhaust, a trip lever, flexible connection between said dog and said trip lever, and a trip adjacent the rail-road rails to actuate said trip lever, substantially as and for the purpose set forth.

7. In an apparatus of the character described, a valve adapted to control the admission and exhaust of air, a spring to operate said valve in one direction, a stem to operate said valve in the opposite direction, spring actuated dog mechanism to prevent the operation of spring, spring actuated latch mechanism adapted to engage said stem when released by said spring-pressed dog, and prevent manual operation of said stem, a hooked lever to engage said latch mechanism, and maintain it normally out of engagement with said stem, a bell-crank lever to operate said hooked lever, a bar pivoted to one arm of said bell-crank lever having an off-set shoulder thereon and adapted to engage and operate the operating mechanism of said spring-pressed dog, tilting, laterally movable fingers adapted to engage said off-set shoulder, trip-levers, trips adjacent to the rail-road tracks adapted to engage and move said trip-levers, connections between said trip-levers and said laterally movable tilting fingers, governor mechanism, mechanism operated thereby adapted to give lateral movement to said fingers, and a vertically movable post controlled by said governor so as to control the operation of said latch, substantially as and for the purpose set forth.

8. In an apparatus of the character described, a valve to control the admission and exhaust of air, a spring to operate said valve in one direction, a stem to operate said valve in the opposite direction, spring-pressed dog mechanism adapted to engage said valve-

stem and maintain said spring in a compressed condition, a spring actuated latch adapted when released, to engage said valve-stem and lock the same to manual operation, lever and hook mechanism adapted to normally retain said latch out of engagement with said valve-stem, a bar pivoted to said lever and hook mechanism and engaging said spring-pressed dog mechanism and having an offset shoulder thereon, laterally movable tilting fingers adapted to be moved laterally over said shoulder, rearwardly extending arms on said fingers, a governor mechanism, mechanism actuated by said governor mechanism to give lateral movement to said tilting fingers, a circuit interrupter operated by said governor mechanism, brushes in contact therewith, an electro-magnetic mechanism adapted by means of mechanical connections to cause one of

said fingers to tilt when over said off-set shoulder and force said spring-pressed dog out of engagement with said valve-stem and said lever and hook mechanism to release said spring actuated latch, a vertically movable post controlled by said governor, swinging guide mechanism to support the upper end of said post, lever mechanism for controlling said swinging guide adapted to be operated by said rearward extensions on said fingers, and means controlled by said valve-stem for retaining said swinging guide in its abnormal position, substantially as and for the purpose set forth. 25 30

In testimony whereof I affix my signature, 35 in presence of two witnesses.
